UNITED STATES PATENT OFFICE.

EDWIN C. BROWN, OF PHILADELPHIA, PENNSYLVANIA.

COLLAPSIBLE BUCKET OR PAIL.

SPECIFICATION forming part of Letters Patent No. 724,255, dated March 31, 1903.

Application filed November 14, 1902. Serial No. 131,395. (No model.)

To all whom it may concern:

Be it known that I, EDWIN C. BROWN, a citizen of the United States, residing at Philadelphia, in the county of Philadelphia and State 5 of Pennsylvania, have invented new and useful Improvements in Collapsible Buckets or Pails, of which the following is a specification.

This invention relates to collapsible buckets or pails, and the purpose of the same is 10 to provide a simple and effective construction whereby a device of this class may be reduced to compact form for storage or other purposes, and having means coöperating with the parts thereof whereby the latter may be 15 sustained in operative relation without liability of accidental displacement.

The invention consists in the construction and arrangement of the several parts which will be more fully hereinafter described and 20 claimed.

In the drawings, Figure 1 is a perspective view of a bucket or pail embodying the features of the invention and shown arranged for use. Fig. 2 is a transverse vertical section 25 of the same. Fig. 3 is a side elevation of the improved device shown collapsed.

Similar numerals of reference are employed to indicate corresponding parts in the several views.

30 The numerals 1, 2, and 3 designate telescopic sections from which the pail is made up, each successively increasing in diameter, and the lower section 1, having a base-flange 4 integral therewith or secured thereto and 35 against which the sections 2 and 3 are adapted to be telescoped, as clearly shown by Fig. 3. The bucket or pail embodying the features of the invention simulates an ordinary telescopic or folding drinking-cup, and secured 40 to the upper section is a bail 5, by which the entire pail may be transported from one point to another. While it is possible to have the upper edge of one section and the lower edge of the next section throughout the series of 45 sections frictionally engage each other with such degree of tightness as to prevent the bucket or pail under ordinary circumstances from telescoping, it will be understood that it is far preferable to provide means whereby 50 the pail structure may be rendered substantially rigid when the several sections are disposed in operative position or arranged to

form a practical bucket or pail. For this purpose opposite stretchers 6 are provided; and each comprises a series of three members 7, 8, and 9, the member 7 being pivotally attached at its lower end to an upstanding ear or projection 10, rising from the periphery of the base-flange 4. The upper end of the member 9 is pivotally attached to the 60 rim of the section 3, and the opposite ends of the member 8 are pivotally connected, respectively, to the lower and upper ends of the members 9 and 7. On each stretcher flat sleeves 11 are slidably mounted to render the 65 joints between the members 9 and 7 and the member 8 rigid to prevent each stretcher from moving when it is desired to maintain the sections of the bucket or pail in operative 70 distended relation. The stretchers 6 are at 75 diametrically opposite points in relation to the pail and when extended are in vertical lines, so as to clear the base-flange 4 for the reception of the sections 2 and 3 when the latter are pushed downwardly in telescoping the bucket or pail. When it is desired to telescope the bucket or pail, the sleeves 11 are pushed clear of the joints between the members 9 and 7 and the member 8, so as to 80 permit said members to closely fold, as shown 85 by Fig. 3. The sleeves 11 are contracted at one extremity, as at 12, (see Fig. 2,) to render them effective in clamping the joints between the members of the stretchers.

The proportions of the pail and coöperating parts may be varied at will, and it will be seen that a very convenient construction is provided without adding materially to the expense of manufacturing this class of devices. It will be understood that the sections, as well as the stretchers, will be preferably formed of metal, though other materials may be used in certain grades of pails—such, for instance, as papier-mâché—or from compositions or compounds.

Having thus fully described the invention, what is claimed as new is—

A bucket or pail, comprising telescopic sections increasing in diameter toward the upper section, the bottom section having a surrounding base-flange having a diametrical extent approximately equal to the rim of the upper section, stretchers made up of movable members pivotally attached to each other and

terminally secured to the rim of the upper section and the periphery of the flange of the lower section so as to dispose the said stretchers vertically when distended, the stretchers being foldable against the flange of the lower section when the several sections are collapsed, and means on the stretchers for rendering the pivotal joints thereof rigid to sus-

tain the sections in immovable position when distended to form a pail.

In testimony whereof I affix my signature in presence of two witnesses.

EDWIN C. BROWN.
